Application August 21, 1951, Serial No. 242,905

Claims priority, application Brazil August 22, 1950

10 Claims. (Cl. 123—16)

My invention relates to a hydraulic machine operable as a fluid pump or compressor or as an internal-combustion engine.

The general object of the present invention is to provide a hydraulic engine of the rotary type, i. e. a machine wherein the working medium either acts upon or is acted upon by a rotor without the intermediary of conventional reciprocating pistons and crank shafts, which is of greater efficiency than similar machines hitherto proposed and wherein friction and wear are greatly reduced.

It is another object of this invention to provide means for more effectively lubricating and cooling a machine of the character referred to.

A more particular object of my invention is to provide a highly efficient multi-stage fluid pump in which the several stages are combined in a single rotor.

It is also an object of the instant invention to provide a machine of the character described which is adapted to be used, with minor modifications, either as a pump of substantially constant delivery rate or pressure or as a motor with substantially constant torque.

The above and other objects, which will subsequently appear, are realized in accordance with the invention by the provision, in combination with a housing and a rotor in said housing having one or more chambers, of a fluid piston movable in each chamber in radial direction with respect to the rotor axis, such radial movement being due to the cam shape of the housing (which may be non-circular, or circular but eccentric with respect to the rotor axis) and to the centrifugal force of the moving rotor tending to displace the fluid outwardly. The fluid constituting the piston, which advantageously is constituted by a liquid also serving as a lubricant and/or coolant, is in direct contact with a second fluid, representing the working medium, which in the case of a pump is drawn in through suitable intake ports and expelled through suitable outlet ports by the reciprocating motion of the piston fluid. In the case of a motor the working fluid, constituted by a combustible mixture (or air in the case of a diesel engine), is aspirated, compressed and expelled by the fluid piston during the non-working strokes of an operating cycle and is exploded during a working stroke, thereby acting upon said piston to cause the fluid thereof to exert pressure upon the chamber walls with a peripheral component imparting rotary movement to the rotor. The constancy of the pump output or of the motor torque can be enhanced by increasing the number of piston chambers in the rotor; if this number is even and greater than two, then the chambers can be so arranged as to balance the radial forces acting upon the rotor shaft, thus reducing wear and stress. By intercalating a plurality of sets of chambers of different sizes it is possible to obtain a multi-stage pump or compressor operating in the same manner as the simple one-stage pump described above.

The invention will be better understood from the following description of certain embodiments, reference being had to the accompanying drawing in which:

Fig. 1 is a cross section through the housing and parts

2

of the rotor of an internal combustion engine representing a first embodiment of the invention;

Fig. 2 is a section on the line 2—2 of Fig. 1;

Fig. 3 is a section through the housing and parts of the 5 rotor of a pump or compressor according to the invention;

Fig. 4 is a section on the line 4—4 of Fig. 3;

Fig. 5 is a section through the housing of another form 10 of compressor embodying the invention; and

Fig. 6 is a section on the line 6—6 of Fig. 5.

Throughout the drawing, corresponding elements in the several embodiments have been indicated by similar reference numerals differing only in their hundreds digit.

Figs. 1 and 2 show an internal-combustion engine 500 15 adapted to aspirate through the inlet port 511 a motive fluid, such as air or a combustible mixture, which after compression in one of the chambers 505 is brought to explosion by suitable means, here shown by way of example as a fuel injection nozzle 531 positioned substantially at a point of maximum compression. The spent gases are expelled via exhaust port 512. It will be obvious that the nozzle 531 may be replaced by other explosive-promoting means, such as a spark plug. Ports 511 and 512 are connected, respectively, to ducts 509 20 and 510 both provided in right-hand end plate 502a (as viewed in Fig. 2) which also carries the fuel injector 531. The ducts communicate with the chambers 505 by way of apertures 508', 508'', respectively, provided in stationary packing disk 521a adjacent end plate 502a.

Various features shown in Figs. 1 and 2 are as applicable to a motor as to a pump or compressor. Thus the number of operating cycles per revolution of the rotor 503 is made double that of a compressor as shown in Figs. 3 and 4, described below, modifying the shape 25 of the housing 501 so as to give a roughly cloverleaf-shaped configuration, with four high points and four low points in place of the two high points and two low points of the elliptical housing shown in subsequent figures. The housing, accordingly, is formed with four lobes shown

30 at 532a, 532b, 532c and 532d, respectively. Whereas, however, in a pump or compressor all of these lobes would preferably be equal, it will be understood that in an internal-combustion engine alternate lobes, such as the lobes 532a and 532c, each correspond to the suction-compression half-cycle while the remaining lobes, such as the lobes 532b and 532d, each correspond to the explosion-expulsion half-cycle; I prefer to enlarge the latter over the former by increasing the maximum radius of each lobe 532b and 532d over that of each lobe 532a and 532c, as shown.

50 The housing 501 is filled with a piston fluid 513, e. g. water, which during rotation of rotor 503 moves alternately away from and toward the rotor axis as a result of centrifugal forces and the shape of the peripheral housing wall; this motion of the piston fluid, in turn, imparts the necessary suction and compression to the aspirated working fluid. The piston fluid 513 is confined between slides 507 which are guided at their forward sides merely by projections 514, the rear surface of each slide abutting a solid backing member 533. In operation, the pressure exerted during the explosion stroke upon the piston fluid 513 of a chamber, as the latter rotates clockwise, say, from the nadir point of the housing to the high point of the next lobe 532b, acts in opposite tangential directions upon the two chamber walls each formed by a backing member 533 extended by the associated slide 507; since, however, the leading slide during that part of a cycle will project further outwardly than the trailing slide, there will be a larger surface exposed to this pressure forwardly than rearwardly of the chamber, hence a resultant force will come into play which drives the rotor forwardly.

Figs. 1 and 2 also show how the piston fluid, which in this case may also be a heavy oil or other liquid not combustible at the operating temperatures of the motor, is also utilized for purposes of lubrication and cooling. The liquid from tank 523 (which may be equipped with cooling apparatus well known per se) enters the machine through feeder pipe 524 and valve 528, reaching the inlet 532d by way of an extension pipe 524'. The liquid then enters the chambers 505, part of the excess returning directly to the tank via drain pipe 525. The chambers 505 also communicate, however, with a conduit 534 leading over a valve 543 to shaft bearing 535b in end plate 502b, the liquid thence passing along the splined portion of shaft 504 toward end plate 502a and shaft bearing 535a thereof. At the left-hand side of the rotor 503 (as viewed in Fig. 2) the liquid also reaches, via a channel 536, an annular pressure chamber 537; at the right-hand side of the rotor it accumulates in an annular chamber 538 whence a drain 539 returns it to the tank via a valve 540. In order that the required pressure be developed in chamber 537 it is, of course, necessary for the conduit 534 to enter the housing 501 at a suitable angle, e. g. tangentially in the manner illustrated for the high-pressure port leading to pipe 525. A pressure-equalizing channel 541, interconnecting diametrically opposite minimum-radius points of the housing, also communicates with the tank 523 by way of a safety valve 542.

The piston liquid 513, apart from lubricating and cooling the machine through the channel system just described, also exerts pressure upon the rotor 503, by virtue of its accumulation in chamber 537, in a direction such as to urge this rotor firmly against the valve disk 521a. This pressure, it may be noted, may be regulated with the aid of valves 543 and 540, such pressure regulation being either manual or automatic. Valves 528 and 542, as will be observed, have been illustrated as self-adjusting in response to fluid pressure within housing 501.

Figs. 3 and 4 show a two-stage compressor 400 whose slides 407 are so spaced as to form alternately wide chambers 405a and narrow chambers 405b. Right-hand end plate 402a (as viewed in Fig. 11) contains a first inlet duct 409a which is connected to entrance port 411 and communicates, in certain positions, of rotor 401, with the larger chamber 405a by way of side apertures 408a; this plate is also provided with a first outlet duct 410a which is connected to the entrance side of an interstage coupling duct 430 and communicates, in other positions of the rotor 403, with the same chambers 405a by way of said apertures 408a. Left-hand end plate 402b contains a second inlet duct 409b which is connected to the exit side of coupling duct 430 and communicates, in certain positions of the rotor, with the smaller chamber 405b via said apertures 408b; this plate is also provided with a second outlet duct 410b which is connected to the discharge port 412 and communicates, in other positions of the rotor, with the same chambers 405b by way of said apertures 408b. It will thus be seen that working fluid, entering by way of low-pressure port 411, is first compressed in the stage formed by chambers 405a, then passes over duct 430 to the chambers 405b whose volume is reduced, with respect to chambers 405a, in accordance with the precompression already imparted to the fluid and which represents the second stage, the output of the latter stage being delivered at the high-pressure port 412. Piston fluid 413 is again admitted and removed via ducts 426 and 427, respectively.

Figs. 5 and 6 show a compressor 600 characterized by a novel arrangement of its inlet and outlet openings. The piston fluid 613 (e. g. water), coming from tank 623, rises through a pipe 624 (not visible but indicated in dot-dash lines) and enters the chambers 605 through an inlet opening 643 located close to the chamber bottom in the valve disk 621a. The return to the tank takes place by way of a peripheral channel 641 and an opening 646 in the housing 601. Admission of the working fluid (e. g. air), from an entrance port (not shown), is via a duct

609 in the housing and an opening 608' in disk 621a; the fluid then leaves by way of opening 608" in disk 621a and duct 610 in housing 601 to reach the exhaust port 612 after passing through a liquid separator 644 communicating with the tank 623 through apertures 645. It will be noted from Fig. 5 that the entrance opening 608' widens from a point near the minor axis of the elliptical housing toward a point near the major axis thereof, thereby enabling the rate of working-fluid aspiration to increase with increases in effective chamber volume due to a receding of the piston fluid. A compressor of great suction power is thereby created.

From the foregoing description it will be apparent that the invention offers the following advantages not particularly pointed out hereinabove:

A pump or compressor may operate at a very high volumetric efficiency (theoretically up the 100%), by virtue of the fact that the fluid piston can be caused not only completely to fill out the rotor chambers but also to penetrate adjacent channels such as, for example, the valve opening 608" and part of the discharge duct 610 of Figs. 5 and 6. Such maximum volumetric efficiency may be attained by admitting sufficient liquid into the rotor chambers, yet at the same time it will be apparent that a stepless adjustment of the pump output between 100% (full load) and almost zero (idling) may be obtained through the simple expedient of changing the amount of liquid available inside the housing, thus altering the height of the fluid piston and varying the rate of percentage variation of the chamber volume with each piston stroke.

The presence of liquid at the interfaces of all relatively movable elements associated with the rotor chambers furthermore provides a gas-tight seal at the boundaries of each chamber, thereby substantially preventing loss of output due to escaping working fluid.

In the case of a motor, as shown in Figs. 1 and 2, it will be possible to energize any number of piston chambers 505 with not more than two explosion-promoting devices, such as the nozzle 531 and a similar nozzle, not shown, located at a diametrically opposite point of the housing. The presence of two nozzle (or sparkplugs) is desirable for balancing purposes, yet even with a single nozzle all chambers would successively pass by the same for ignition of their charges. Furthermore, the fuel injected by the nozzle mixes more intimately with the air content of the chamber, compared with conventional diesel engines, by virtue of the fact that said air moves rapidly past the nozzle in a direction perpendicular thereto.

With reference to the two-stage compressor of Figs. 3 and 4 it may be stated that the two sets of chambers 405a, 405b need not be serially interconnected but may be utilized independently, as where two outputs of different gases and/or different pressures are required. The same principle, furthermore, is also applicable to internal-combustion engines of the type shown in Figs. 1 and 2, one set of chambers serving for the aspiration and compression, the other for the ignition and expulsion of the motive fluid.

In all embodiments as will be readily understood, the action of the centrifugal force in maintaining the slides in contact with the peripheral housing wall may be supplemented by the force of springs or the like.

Accordingly, while the invention has been described with reference to certain specific embodiments only, it is to be understood that the same may be modified in various ways without thereby departing from its scope as defined in the appended claims.

I claim:

1. In a diesel-type engine, in combination, a rotor, a housing enclosing said rotor and having a stationary side wall adjacent a face of said rotor, said rotor having a chamber open at said face but closed by said wall, fuel injector means in said wall positioned for periodic communication with said chamber, a liquid in said housing

partly received in said chamber and forming a piston therein, means including said liquid piston for compressing a charge in said chamber immediately prior to its passage past said fuel injector means and for ejecting an exploded charge from said chamber, and means including said liquid for urging said rotor into close contact with said wall.

2. In a hydraulic machine, in combination, a rotor, a housing enclosing said rotor and having a stationary side wall adjacent a face of said rotor, said rotor having a chamber open at said face but closed by said wall, said wall having an inlet port and an outlet port for fluid to be admitted into said chamber, said ports being positioned for alternate communication with said chamber, a liquid in said housing partly received in said chamber and forming a piston therein, means including said liquid piston for alternately aspirating said fluid through said inlet port and expelling said fluid through said outlet port, and means including said liquid for urging said rotor into close contact with said wall.

3. In a hydraulic machine, in combination, a housing, bearing means in said housing, a rotor journaled in said bearing means within said housing, said rotor having a chamber open toward said housing, said housing having an inlet port and an outlet port for fluid to be admitted into said chamber, said ports being positioned for alternate communication with said chamber, a liquid in said housing partly received in said chamber and forming a piston therein, means including said liquid piston for alternately aspirating said fluid through said inlet port and expelling said fluid through said outlet port, and conduit means in permanent communication with said chamber and with said bearing means for admitting part of said liquid to said bearing means, thereby lubricating the latter.

4. In a hydraulic machine, in combination, a rotor, a housing enclosing said rotor and having a peripheral portion of varying distance from the axis of said rotor, radially slidably vane means in said rotor defining at least one chamber in said rotor open toward said peripheral housing portion, stationary valve plate means in said housing in face-to-face contact with said rotor, said valve plate means having inlet port means and outlet port means for fluid to be admitted into said rotor chamber, said rotor being apertured for communication of said rotor chamber with said inlet and outlet port means, respectively, in different angular positions of said rotor, a pressure chamber located in said housing at one side of said rotor, a duct extending from said pressure chamber toward said peripheral housing portion, thereby connecting said pressure chamber with said rotor chamber, a liquid occupying said pressure chamber, said duct and part of said rotor chamber, said liquid forming a piston in said rotor chamber reciprocating upon rotation of said

rotor, thereby alternately aspirating and expelling said fluid through said inlet and outlet port means, respectively, and means including said liquid in said pressure chamber for urging said rotor into close contact with said

5 valve plate means, said duct entering said peripheral housing portion at an acute angle to the path of rotation of said liquid piston.

5. The combination according to claim 4, further including storage means for said liquid, an overflow connection and a return connection between said storage means and said peripheral housing portion, and valve means in said connections for regulating the pressure in said pressure chamber.

6. The combination according to claim 5, wherein said peripheral housing portion is symmetrical with respect to the rotor axis, one of said connections including a channel opening into said housing portion at diametrically opposite points for equalizing the pressure thereat.

7. The combination according to claim 4, wherein said 20 housing is provided with bearing means for said rotor and with a channel connecting said bearing means with said pressure chamber, thereby admitting liquid under pressure to said bearing means for lubricating the latter.

25 8. The combination according to claim 4, wherein said rotor is provided with a plurality of sets of interleaved chambers, said inlet and outlet port means comprising a plurality of inlet ports and outlet ports each positioned for communication with a respective set of chambers.

30 9. The combination according to claim 4, wherein said inlet port means comprises a portion of said valve plate means having an opening whose width increases in the direction in which the spacing of said peripheral housing portion from said rotor axis increases, thereby causing the rate of aspiration of said fluid to rise with increasing effective volume of said rotor chamber.

10. The combination according to claim 4, including storage means for said liquid, feed means connecting said storage means with said peripheral housing portion, and a connection between said outlet port means and said storage means, said connection including liquid separator means for returning liquid entrained by said fluid to said storage means.
